US00D958780S

(12) **United States Design Patent** (10) **Patent No.:** **US D958,780 S**
(45) **Date of Patent:** **** Jul. 26, 2022**

(54) **ELECTRONIC DEVICE**

- (71) Applicant: **Samsung Electronics Co., Ltd.**, Suwon-si (KR)
- (72) Inventors: **Hyok-Su Choi**, Suwon-si (KR); **Jong-Bo Jung**, Suwon-si (KR); **Ji-Young Lee**, Suwon-si (KR)
- (73) Assignee: **SAMSUNG ELECTRONICS CO., LTD.**, Suwon-si (KR)
- (**) Term: **15 Years**
- (21) Appl. No.: **29/732,686**
- (22) Filed: **Apr. 27, 2020**

(30) **Foreign Application Priority Data**

- Mar. 19, 2020 (KR) 30-2020-0012310
- (51) LOC (13) Cl. 14-03
- (52) U.S. Cl. ..... USPC **D14/248**
- (58) **Field of Classification Search**

(57) **CLAIM**

The ornamental design for an electronic device, as shown and described.

DESCRIPTION

FIG. 1 is a front perspective view of an electronic device showing our new design according to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a rear perspective view thereof; FIG. 9 is a front perspective view of an electronic device showing our new design according to a second embodiment; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a rear perspective view thereof.

The dashed broken lines in the figures illustrate portions of the electronic device that form no part of the claimed design. The figures are illustrated to show contrasting appearance. Areas of the electronic device that appear in different shades of gray represent areas with contrasting appearances.

1 Claim, 16 Drawing Sheets
